UNITED STATES PATENT OFFICE.

CHARLES C. MUMM, OF MINNEAPOLIS, MINNESOTA, AND JOHN L. STROHM,
OF HANKINSON, NORTH DAKOTA; SAID STROHM ASSIGNOR TO SAID
MUMM.

BOOK-FILE.

SPECIFICATION forming part of Letters Patent No. 739,436, dated September 22, 1903.

Application filed July 31, 1902. Serial No. 117,803. (No model.)

To all whom it may concern:

Be it known that we, CHARLES C. MUMM, of Minneapolis, Hennepin county, Minnesota, and JOHN L. STROHM, of Hankinson, Rich-
5 land county, North Dakota, have invented certain new and useful Improvements in Book-Files, of which the following is a specification.

Our invention relates to improvements in files designed to contain loose sales-slips, ac-
10 counts, memoranda, &c.; and the object of the invention is to provide a file wherein the individual accounts of each customer, when the device is used by a merchant, may be kept and conveniently referred to, one file being
15 appropriated for each customer and the sales-slips detached from the book and placed in its appropriate file whenever a sale is made or at the close of the day's business.

Other objects of the invention will appear
20 from the following detailed description.

The invention consists generally in various constructions and combinations, all as herein-
25 after described, and particularly pointed out in the claims.

25 In the accompanying drawings, forming part of this specification, Figure 1 is a perspective of a book-file with the top cover thrown back and a portion of the back cover broken away to show the construction of the
30 file. Fig. 2 is a similar view showing the spring-actuated presser-arm and the support therefor, and Fig. 3 is an edge view showing the top cover and the presser-arm in their closed position.

35 In the drawings, 2 and 3 represent, respectively, the back and front covers of heavy
30 pasteboard or other suitable material, and 4 a flexible connection between said covers and forming the back of the file, and 5 is a metal
40 reinforcing-plate provided on the back cover near one end and preferably concealed by the lining 6. This plate has an outwardly-turned
45 preferably integral flange 7, substantially parallel with and bracing the back 4 and pref-
erably spaced therefrom to make room for the ends of the presser-arm and the spring bearing
50 thereon and having at its outer edge a lip 9, to which the flexible back 4 is secured by a wire 10 or other suitable means. The rein-

55 forcing-plate is provided with holes to receive
50 filing posts or pins 11, having headed inner

ends that rest upon the back cover and are braced and stayed by said plate and have pointed outer ends to facilitate the filing of
55 loose sheets or leaves thereon. The flange 7 is provided upon each side of the center thereof with slots 12, wherein the ends of a looped
60 presser-arm 13 are inserted. These ends are outwardly turned and provided with heads
65 14, that are engaged by the ends of a flat spring 15, that is preferably secured at a point intermediate to its ends by a rivet or other
70 suitable means to the flange 7. We prefer to provide grooves or depressions 16 in the flange
7 to receive the outwardly-turned ends of the
75 presser-arm and the heads thereon and aid in holding them in place. When the presser-
80 arm is raised to the position shown in Fig. 2, the heads 14 will swing around and bearing upon the spring 15 place the same under ten-
85 sion, pressing it away from the flange 7, and when the presser-arm is lowered the heads will swing back, allowing the spring to return to its normal position, where it will exert its
90 force to hold the arm down upon the leaves.

At the end of the file opposite the presser-
95 arm mechanism we prefer to provide a block
17, upon the outer face of which the name of
the customer may be written or printed to
100 permit the ready location of a customer's file
when placed in the file-case. This block may,
if preferred, be provided with a suitable fas-
tening device (not shown) for holding the
front cover in place.

We claim as our invention—

1. In a book-file of the class described, the combination, with the covers, of a reinforcing-
100 plate provided on the back cover and having an upwardly-turned flange forming a back
plate, a presser-arm carried by said back
plate, paper-holding studs provided on said
reinforcing-plate, and means for causing said
presser-arm to bear with a yielding pressure
105 on the paper upon closing said covers, sub-
stantially as described.

2. In a pocket-book file, the combination,
110 with a back cover, of a reinforcing-plate se-
cured thereon near one end and having an
outwardly-turned flange forming a back
plate, paper-holding studs mounted on said
reinforcing-plate and whereon the sales-slips
115 or memoranda are placed, a presser-arm car-

ried by said back plate, and means for holding said presser-arm in yielding engagement with the paper on said studs, substantially as described.

- 5 3. In a device of the class described, the combination, with a back cover provided at one end with a horizontally and vertically extending plate, posts secured to and extending vertically from the horizontal portion of the 10 plate and having their upper ends free for the reception and removal of memoranda-leaves, and a spring-influenced presser-arm secured to the vertical portion of the plate and arranged to extend beyond the posts and 15 to bear against the memoranda-leaves held by the posts, substantially as described.
4. In a device of the class described, the combination, with a back cover provided at one end with a horizontally and vertically extending plate the vertical portion of which is 20 formed with a longitudinally-raised portion forming a groove and having slots formed in it, posts secured to and extending vertically

from the horizontal portion of the plate and having their upper ends free for the reception and removal of memoranda-leaves, a looped presser-arm having its ends passed through the slots in the longitudinally - extending groove of the plate and outwardly bent to one side of the slots and provided with heads, 25 and a spring secured to the plate and pressing against said heads, substantially as described.

In witness whereof we have hereunto set our hands, CHARLES C. MUMM, at Minneapolis, 30 Minnesota, this 21st day of July, and JOHN L. STROHM, at Hankinson, North Dakota, this 22d day of July, 1902.
